Filed Apr. 27, 1972, Ser. No. 248,350

Term of patent 14 years

Int. Cl. D7—02

U.S. Cl. D7—128

FIG. 1

FIG. 2

FIG. 1 is a front perspective view of a portable microwave oven or similar article embodying our new design with the oven interior lighted, it being understood that the perforated panel which is fragmentarily illustrated in the viewing window continues across the entire surface thereof.

FIG. 2 is a second front perspective view similar to that of FIG. 1, but with the oven interior unlighted.

Both the large oven door at the left and the smaller control panel at the right are furnished with full height and full width tinted glass panels. The oven door is masked to provide a rectangular viewing window that is visible when the oven interior is lighted.

The side of the oven not shown is substantially like the side that is shown, and the back panel is flat and substantially plain.

We claim:

The ornamental design for a portable microwave oven or similar article, as shown and described.
